RIBBON FEED MECHANISM

Jerome B. O'Daniel and Leon E. Palmer, Lexington, Ky., assignors to International Business Machines Corporation, New York, N.Y., a corporation of New York

Filed June 26, 1962, Ser. No. 205,392

13 Claims. (Cl. 197—151)

This invention is directed to ribbon feeding mechanisms for typewriters, and more particularly to mechanisms which are adjustable manually for causing different feeding operations depending on the kind of ribbon used.

The quality of typing obtained with a fabric or cloth ribbon is not the best but the amount of satisfactory typing that can be done with such ribbon and the fact that it is less expensive may make it the most desirable. Typing operations should not take place successively on the same area of a cloth ribbon since time is needed for such area to recover after each use. This ribbon may be fed, however, back and forth many times before it needs to be discarded. Some ink is delivered to the used areas between passes by capillary action and, even though the quantity of print decreases slightly on each pass, it is left to the operator to decide when the ribbon should be changed.

A higher quality of print can be obtained from a plastic ribbon like that disclosed in a co-pending application, Serial Number 171,188, filed February 5, 1962, by H. T. Findlay et al. This ribbon has many small pockets in which ink is entrapped and a small portion of the ink is forced from these pockets on each typing operation. There is no passing of ink between the pockets by capillary action as there is in a cloth ribbon and so there is no need to wait for a recovery of the ribbon after a typing action. A number of high quality printed characters can be obtained when typing successively on the same area of the plastic ribbon. In order to get the maximum use from a ribbon of this type, the feed mechanism is designed to shift the ribbon transversely a slight amount after each character is typed. During this time there is no feeding of the ribbon longitudinally. As each character is typed it overlaps partially the area engaged by the type element during the typing of the preceding character. The transverse motion of the ribbon is such that substantially the full width of the ribbon is subjected to the action of the type elements. After the ribbon has been subjected in one transverse path to a predetermined number of print operations, this number being so limited that high quality print is obtained for each character, the ribbon is then advanced to present a new portion which is again shifted transversely during the printing of another group of characters. The feeding mechanism is so designed that it will not reverse after the ribbon has made one complete pass and a new ribbon has to be installed on the machine. This prevents the operator from using the ribbon beyond the point at which high quality typing is obtained.

At times it may be necessary that the typewriter be used for cutting a stencil. During such times there should be no feeding of the ribbon and it should be left in a low position so the type elements may act on the stencil at a point above the ribbon. The ribbon feeding mechanism of the present invention is provided with manually operated control elements which may be set by the operator for causing any one of the operations mentioned above.

An object of this invention is to provide an improved ribbon feeding mechanism for a typewriter.

Another object is to provide an improved ribbon feeding mechanism which can be adjusted by the operator to feed ribbon in different ways depending on the type of ribbon used.

2

Still another object is to provide a ribbon feeding mechanism which is operable to locate a ribbon in a plurality of different positions transversely of type elements during the typing of characters and then to advance it a short distance longitudinally where it is again shifted transversely of the type elements as characters are typed, such action continuing until the ribbon has been advanced its full length.

Yet another object is to provide a ribbon feed mechanism which operates to feed one type of ribbon longitudinally past typing elements with an automatic reversal in its direction of feed when either end of the ribbon is reached, and being adjustable to feed another type of ribbon longitudinally in steps after it has shifted the ribbon transversely in incremental steps for a predetermined number of typing operations, the mechanism operating with such adjustment to feed the ribbon in only one direction.

The foregoing and other objects, features and advantages of the invention will be apparent from the following more particular description of a preferred embodiment of the invention, as illustrated in the accompanying drawings.

In the drawings:

FIG. 1 is a plan view of the improved ribbon feeding mechanism.

FIG. 2 is a perspective view of a ribbon lift mechanism associated with the feeding mechanism and operable to lift the ribbon varying distances.

FIG. 3 is an enlarged vertical sectional view taken on the plane of the line 3—3 in FIG. 1.

FIG. 4 is a perspective view of means for supporting and driving spools on which ribbon is wound.

Referring to the drawings, and more particularly to FIG. 4, it will be noted that there is shown a pair of ratchet wheels 1 and 2 rotatably supported by a plate 3 and carrying spindles 4 on which ribbon spools may be mounted. A pawl 5 is oscillated while engaging one or the other of the ratchet wheels to cause a driving of one spool so as to wind ribbon on that spool while it is being unwound from the other spool. When the ribbon has been completely wound onto the driven spool, a member 6 is moved into the path of the pawl so it is driven rearwardly by the latter during the next oscillation. At the same time, an arm 7 on the member 6 is positioned 40 in front of a transversely extending arm 8 on a toggle member 10. As the member 6 is moved rearwardly, the toggle member is rocked in a counterclockwise direction and acts through a spring 11 to swing the pawl 5 into engagement with the other ratchet wheel. This mechanism is described completely in U.S. Patent 2,902,136, issued September 1, 1959 to W. B. Whippo and further description herein is believed to be unnecessary.

Formed in the plate 3 adjacent its ends are slots 14 through which screws may be inserted into openings 15 (FIG. 1) in a carrier 16 for a single print head like that shown in the patent. The carrier slides along a shaft 17 and carries with it a sleeve 18 which is keyed for rotation with the shaft while sliding longitudinally thereof. Mounted on the sleeve is a cam 20 which is operable to 50 drive a member 21 slidably mounted on a bracket 22 connected, as shown in FIG. 3, to the carrier 16. One end of the member 21 is bent upwardly to provide a surface 23 which acts on the cam 20, and its other end is also bent upwardly to provide a surface 25 which acts on a member 26 pivotally supported by a pin 27 in a bracket 28 attached by means, not shown, to the plate 3. The lower end of the pawl 5 is loosely mounted on the pin 27 and has a finger 29 acting on the member 26 so that a rocking of the latter in a counterclockwise direction causes the pawl 50 to swing in the same direction against the action of a spring 30. It will be seen that this causes a driving of one or the other of the ratchet wheels 1 and 2.

Mounted on the bracket 22 is a pin 32 which extends upwardly through a slot in the member 21. A spring 33 is connected between this pin and the member 21 for urging the latter toward the cam 20. The shaft 17 is caused to make one revolution on each spring operation and, if the member 21 is subjected to the full action of the cam 20, the pawl 5 is driven a distance to rotate one of the ratchet wheels two teeth. This drive is employed when a fabric ribbon is used in order to advance it far enough so there is no overlapping of ribbon areas engaged by type elements during successive typing operations. When a plastic ribbon like that mentioned above is used, the member 21 is driven only far enough to actuate the pawl 5 for rotating a ratchet wheel one tooth space, and this driving of the member takes place after a predetermined number of print operations have been completed. When the typewriter is being used to cut stencil, the member 21 is held free of the cam 20 so that no feeding of the ribbon takes place.

Control of the movement by the member 21 is accomplished by two latching pawls 35 and 36 pivotally mounted on the bracket 22 and engageable with the edge of a laterally projecting portion 37 on the member 21. Pawl 35 controls movement of member 21 when a plastic ribbon is being used and has two spaced shoulders 38 and 39 which may be located selectively in the path of the projecting portion 37. When the shoulder 38 engages the portion 37, the member 21 is held in a position which permits its actuation by the cam only far enough to rock the pawl for driving a ratchet wheel one tooth. With the member 21 moved to its extreme position by the high point of the cam, the shoulder 39 drops in front of the portion 37 and holds the member 21 free from any action by the cam. During a predetermined number of print operations, the shoulder 39 on pawl 35 holds the member 21, as shown in FIG. 3, to prevent a feeding of the ribbon longitudinally. As soon as the number of print operations has been completed, pawl 35 is lifted only far enough to permit the member 21 to move toward the cam 20 until the portion 37 engages the shoulder 38. The next rotation of the cam moves the member 21 to drive one of the ratchet wheels one tooth and then the shoulder 39 holds the member 21 free of the cam until the predetermined number of print operations has been completed again. Pawl 36 has a single shoulder 40 which is engageable with the portion 37 for holding the member 21 free of the cam 20. This pawl is active to prevent ribbon feed when the mechanism is adjusted for cutting stencil. The mechanisms for controlling pawls 35 and 36 will be described later.

During the operation of the typewriter to print information, it is necessary that the ribbon be raised in front of the type element to effect printing and then be lowered so the operator can see what was printed. When a fabric ribbon is used, the distance lifted is the same for each print operation but this distance may be changed by the operator to either low, medium or high. With the feed mechanism adjusted for plastic ribbon, the distance lifted is different for each print operation. The mechanism shown and described herein is designed to shift the ribbon transversely to twenty-two different positions relative to the type elements before it is advanced longitudinally. It will be appreciated that this may be changed to any figure desired depending on the capacity of the ribbon to give the desired quality of printing.

The mechanism for lifting or shifting the ribbon transversely is shown in FIG. 2 and is generally like that described in U.S. Patent 2,919,008, issued December 29, 1959 to W. B. Whippo. This mechanism comprises a pair of lower lift arms 42 loosely mounted at one end on a rod 43 which is supported, as shown in FIG. 1, by the sides of the carrier 16. Formed integral with the arms 42 is a flange 44 having a downwardly extending finger 45 received within a bifurcated end portion of an arm 46 pivoted on a plate member 47 which is, in turn,

pivotedly connected at 48 to a cross piece of the carrier 16. A handle portion 50 permits manual actuation of the member 47 for forcing the arm 46 against the finger 45 to swing the outer ends of the lift arms 42 upwardly so the ribbon is raised to a position in which it may be easily changed. Connected between the flange 44 and a pin 51 on the member 47 is a toggle spring 52 for holding the member 47 in either position to which it may be moved. A stop pin 53 limits the swinging of the member 47 in either direction.

Extending parallel to the lift arms 42 is a pair of upper arms 55 carrying, at one end, studs 55' which are pivotally supported in the sides of the carrier 16. The outer ends of the arms 42, 55 are pivotally connected to vertically extending ribbon guide members 56, as shown. The arrangement is such that a swinging of the arms 42 on the rod 43 results in a movement of the guide members up or down in a vertical plane. For swinging the arms 42 during each print operation, there is provided a cam follower 57 pivotally connected at 58 to one side of the carrier 16 and engaging a cam 59 on the shaft 17. Formed in the follower 57 is an elongated slot 60 underlying one of the arms 42, and a control rod 61 is slidably received within the slot 60 to act as a support for the arm 42. As the follower 57 is caused to swing about its pivot connection 58, the rod 61 is moved up and down vertically a distance which varies with the location of the rod in the slot 60. This causes the arms 42 to swing and raise or lower the ribbon guide members 56. A spring 62 acts on the rod 61 to urge it toward a position adjacent the pivot point 58. For moving the rod to other positions against the action of the spring, there is provided a lever 64 connected at one of its ends to the rod and mounted at its other end on a pivot pin 65 (FIG. 1) fixed to a transverse portion of the carrier 16. The lever 64 is of arcuate shape, as shown in FIG. 2 and formed at spaced points along its inner edge are detent notches 66. A swinging of the lever 64 manually for positioning the rod 61 to change the amount of ribbon lift is accomplished by a lever 68 mounted on a fixed pivot 69 and having a handle portion 70. Mounted on the lever is a pin 71 which engages the inner arcuate surface of the lever 64 and is received in the notches 66 for holding the lever in positions to effect low, medium or high lift of the ribbon. As the lever 68 is swung in a clockwise direction, the lever 64 is caused to swing counterclockwise and move the rod 61 away from the pivot 58. This results in a higher lifting of the ribbon so printing takes place nearer to its lower edge.

Another means is provided for swinging the lever 64 a slight amount on each print operation to locate the ribbon in a different transverse position. This means comprises a lever 74 (FIG. 1) mounted on the pivot pin 65 and having a finger 75 engageable with a pin 76 on the lever 64. Formed on the lever 74 is a projecting portion 77 which engages a cam 78 fixed to turn with a ratchet wheel 80 on a stationary pivot 81. The lever 74 may be swung either to its operative position shown in FIG. 1 in which it controls the lifting of the ribbon or to an inoperative position in which the projecting portion 77 is free of the cam 78 and the finger 75 is removed from the pin 76. For changing the position of the lever, there is provided in its right end a slot 83 slidably receiving a pin 84 carried by a manually actuated lever 85 which swings about a connecting element in one of the openings 15. The lever 74 is held in either position to which it is moved by a spring 86.

With the lever 74 in its operative position as shown, the latching pawl 35 is operative to control the movement of the member 21 which actuates the ribbon drive pawl 5. During this time, the latching pawl 36 is held in an inoperative position by means to be described later. Formed on the pawl 35, as shown in FIG. 3, is a tail portion 88 which is urged by a spring 89 in a direction to engage the pawl with the projecting portion 37 on the member 21. Cooperating with the tail portion is a hook-

shaped arm 90 on a member 91, FIG. 1, which swings about a stationary pivot 92. Extending from the member 91 to a point overlying the ratchet wheel 80 is an arm 93 having an end portion 94 lying in the path of a stud 95 projecting from the side of the cam 78.

Driving of the ratchet wheel 80 is effected by a dog 96 engaging teeth on the wheel and connected to a lever 97 pivoted at 98 and having a follower portion 99 engaging the cam 20. The ratchet wheel 80 is driven one tooth on each rotation of the shaft 17 and this takes place once for each print operation. There are twenty-two teeth on the ratchet wheel 80 as shown in FIG. 1 and this provides the means to shift the ribbon transversely to twenty-two different positions relative to the type elements before the ribbon is advanced longitudinally. Obviously, this number can be changed to any figure desired depending on the ribbon employed. As a stepped rotation of the ratchet wheel takes place, the cam 78 rotates and rocks the lever 74 slightly so its finger 75 either positively swings the lever 64 counterclockwise or permits this lever to swing clockwise under the action of the spring 62 on the control rod 61. In either case, the position of the control rod is shifted slightly so as to increase or decrease the lifting of the ribbon. When the cam 78 reaches a position in which the stud 95 engages the end portion 94 of the arm 93, the next stepping of the ratchet wheel results in a rocking of the member 91 to engage its hook-shaped arm 90 with the tail portion 88 of the latching pawl 35. The movement of the member 91 is just sufficient to raise the pawl until its shoulder 39 is out of the path of the projection 37 so the member 21 moves toward the cam 20 until the projection engages the shoulder 38. The next rotation of the cam 20 results in a driving of the member 21 so it rocks the feed pawl 5 to drive one of the ratchet wheels for the ribbon spools a distance of one tooth space. As the member 21 is driven to advance the ribbon, the ratchet wheel 80 also turns and causes the stud 95 to slide off the end portion 94 of the arm 93. Member 91 then rocks in a direction to release the tail portion of the pawl 35 and permit the latter to engage its shoulder 39 with the portion 37 for holding the member 21 free of the cam 20 until another rotation of the cam 78 is completed.

While the mechanism is operating as described above to produce an incremental transverse shifting of the ribbon, it is necessary that the manually operated lever 68 be in a position which permits movement of the control rod 61 under the action of its spring 62 to a point effecting a lift of the ribbon until its upper portion is engaged by printing elements. This is the position of the control rod producing minimum lifting of the ribbon and is the position to which the control rod is permitted to move when the manually actuated lever 68 has its pin 71 located in the third notch 66 from the left end of the lever 64 as seen in FIG. 2. The control rod 61 is now free for movement in one direction under the action of the spring 62 and can be moved in the opposite direction by the finger 75 on the lever 74.

To assure that the lever 68 is moved to its proper position when the mechanism is adjusted to lift the ribbon to different positions during typing, there is provided a member 101 mounted at one end on the pivot 69 and having a finger portion 102 extending past the left side of the handle portion 70 on the lever 68. The other end of the member 101 carries a button 103 which is slidably received in a slot 104 formed in a bar 105, and another slot 106 in the bar slidably receives a button 107 on a bracket 108 fixed to the carrier 16. The bar 105 is provided with a hooked end 109 which receives an end portion of the pin 84 as the lever 85 is swung clockwise. A spring 110 is connected between the bracket 108 and the bar 105 for holding the latter in the position shown.

When it is desired to use the mechanism for feeding a fabric ribbon, the lever 85 is rotated manually in a clockwise direction from the position shown in FIG. 1. This

results in a sliding of the pin 84 in the slot 83 to effect a swinging of the lever 74 in a clockwise direction. The lever 85 is rotated until the pin 84 engages the end of the bar 105 and slides the latter to the left on the button 107. This sliding motion of the bar is continued until the right end of the slot 104 engages the button 103 and swings the member 101 clockwise until it engages a projecting portion 111 on the member 91, causing the latter to pivot clockwise until its hooked arm 90 rocks the latching pawl 35 completely out of the path of the projection on the member 21. During this time, pin 84 slides into the hooked end 109 so that later rotation of the lever 85 counterclockwise results in a positive movement of the bar 105 to the right. Lever 85 is held in its new position by the action of the spring 86. The swinging of the lever 74 clockwise results in a movement of its projecting portion 77 to a position free of the cam 78 and also in a movement of its finger portion 75 away from the pin 76 so the lever 64 can swing clockwise until it is stopped by engagement with the pin 71 on the manually operated lever 68. The vertical lifting of the ribbon is now determined by the position of the lever 68 and remains the same for each print operation. As the member 91 is rocked to lift the latch pawl 35 free of the member 21, the arm 93 on the member is moved so its end portion 94 is out of the path of the stud 95 on the cam 78. Ratchet wheel 80 continues to be driven as the shaft 17 rotates but it has no effect on the operation of the ribbon feed mechanism. Latching pawl 36 continues to be held free of the member 21 by means which will be described shortly. Since nothing is now obstructing movement of the member 21, it follows the cam 20 during its full revolution and actuates the ribbon feeding pawl 5 to drive the ratchet wheel 1 or 2 a distance of two teeth. When the ribbon has been fed its full distance in one direction, the pawl 5 is transferred from one ratchet wheel to the other for feeding the ribbon in the opposite direction.

With the parts of the feed mechanism in the positions shown in FIG. 1 to feed a plastic ribbon, the feed pawl 5 is in a position to drive the ratchet wheel 2 for feeding the ribbon from left to right. For moving the pawl to this position and holding it there to prevent a reversal of the ribbon feed, there is provided on the sliding bar 105 a projecting portion 112 which is engageable with an arm 114 (FIG. 4) of the toggle member 10. As the bar 105 moves to the right under the action of the pin 84 on the hooked portion 109, the finger 112 acts on the arm 114 to swing the toggle member 10 to a position in which it pulls the pawl 5 into engagement with the wheel 2.

As mentioned above, it may be desirable at times to use the typewriter for cutting stencil and the mechanism described should be prevented from either lifting the ribbon or feeding it longitudinally. After the lever 85 is rotated clockwise from the position shown in FIG. 1 to the position conditioning the mechanism for fabric ribbon feed, the lever 68 is free for rotation manually to shift the pin 71 along the inner arcuate surface of the lever 64. With the lever 68 swung to its extreme left hand position, the rod 61 is held at a point in the slot 60 to give maximum lift of the ribbon for effecting typing on the low part of the ribbon. As the lever 68 is swung counterclockwise, the rod 61 moves in the slot 60 toward the pivoted end of the member 57 and reduces the lift of the ribbon. With the lever 68 in the position shown in FIG. 1, the amount of ribbon lift is only sufficient to effect engagement of the print elements with its upper portion. When the lever 68 is swung counterclockwise still further to a stencil cutting position, the rod 61 is located in the slot 60 over the pivot point 58 for the member 57 and no lifting of the ribbon takes place.

Formed on the lever 68 adjacent its pivoted end is a cam portion 116 which acts against a tail piece 117 on the latching pawl 36, as shown more clearly in FIG. 3, for holding the pawl out of engagement with the projec-

tion 37 on the member 21. As the lever 68 is turned counterclockwise from the position in FIG. 2 to its stencil cutting position, the cam portion 116 moves away from the tail piece 117 and permits the pawl 36 to drop to its operative position. When the member 21 is driven outwardly by the cam 20 on the first rotation of the shaft 17, the shoulder 40 on the pawl 36 drops in back of the projection 37 and holds the member 21 from following the cam. During this time, no feeding of the ribbon takes place.

When shifting from one type of ribbon to another, it is desirable that the member 21 be released from the pawls 35, 36 so its position is controlled automatically depending on the positions of the manual controls. Member 21 should also be released for engagement with cam 20 when shifting to plastic ribbon in order to assure that the drive pawl 5 is in a position free of the ratchet wheels so it may be moved transversely, if necessary, into driving relationship with ratchet wheel 2. For lifting pawls 35, 36 when the ribbon is being changed, there are provided hooked portions 120, 121 on the pawls engageable by the flange 44 only when the ribbon guides 56 are raised by manual actuation of the member 47.

While there have been shown and described the fundamental novel features of the invention as applied to a preferred embodiment, it will be understood that it may be modified and embodied in various forms without departing from the spirit of the invention.

What is claimed is:

1. A mechanism for moving an inked ribbon transversely and longitudinally relative to a point of contact between a print element and a platen comprising, in combination:

guiding means for said ribbon,

means supporting said guiding means for movement in a direction extending transversely of said ribbon to locate the latter in different vertical positions relative to said point of contact,

a member movable to different positions relative to said supporting means and acting on the latter for transmitting motion thereto, said member adapted to be driven in each of its different positions for transmitting a different motion to said supporting means, a pair of spindles for supporting spools having said ribbon wound thereon and extending through said guiding means,

means including a pawl for imparting stepped rotation to one of said spindles to effect a feeding of said ribbon longitudinally,

a movable element associated with said pawl for driving the latter,

cam means operating on each printing action by said print element for driving said member and said movable element,

a latch for holding said movable element free of said cam means after each driving by the latter,

means operating on each printing action for shifting said member relative to said supporting means,

and means operating after a predetermined number of printing operations for disengaging said latch from said movable element.

2. The mechanism of claim 1 in which said means for shifting said member includes:

a ratchet wheel,

means operating on each printing action for advancing said ratchet wheel,

a cam fixed to said ratchet wheel for rotation therewith,

and a lever arranged for actuation by said cam and operatively connected to said member for shifting the latter.

3. A mechanism for moving an inked ribbon selectively either different distances transversely relative to a point of contact between a print element and a platen on each print operation and then advancing the ribbon a

unit distance after a predetermined number of print operations or moving it a fixed distance transversely and advancing it on each print operation comprising, in combination:

a ribbon guide,

a member acting on said guide and adapted to be driven for moving said ribbon in a transverse direction, said member being movable to different positions relative to said guide for varying the distance driven,

means including an element adapted to be oscillated for effecting a stepped feeding of said ribbon longitudinally,

a first cam means operating on each print action for driving said member,

a second cam means operating on each print action for moving said oscillated element in one direction,

a latch engageable with said oscillated element for holding it free of said second cam means,

means including a control cam which is advanced in steps on each print action,

a first lever adapted to be actuated by said control cam for moving said member to different positions,

a second lever adapted to be actuated for releasing said latch from said oscillated element,

means moving with said control cam and operating after a predetermined number of print actions for actuating momentarily said second lever,

and manually operated means for moving said first lever to a position free of said control cam and moving said second lever to a position for holding said latch released.

4. The mechanism of claim 3 including:

a manually actuated control element for moving said member to any one of different positions when said first lever is moved to a position free of said control cam and said second lever is moved to a position holding said latch released.

5. The mechanism of claim 4 including:

a second latch engageable with said oscillated element for holding it free of said second cam means, and means moving with said manually actuated control element for holding said second latch normally out of engagement with said oscillated element, said last mentioned means operating to release said second latch when said control element is moved to a position locating said member so that no transverse motion of said ribbon takes place.

6. The mechanism of claim 3 including:

a pair of spindles for supporting spools having said ribbon wound thereon and extending through said guiding means,

a ratchet wheel fixed to each of said spindles,

a feed pawl engageable with either of said ratchet wheels and arranged in driven relationship with said oscillated element,

and means for holding said feed pawl in engagement with only one of said ratchet wheels as long as said first lever is in a position to be actuated by said control cam.

7. A mechanism for moving an inked ribbon selectively either different distances transversely relative to a point of contact between a print element and a platen on each print operation and then advancing the ribbon a unit distance after a predetermined number of print operations or moving it a fixed distance transversely and advancing it on each print operation comprising, in combination:

a ribbon guide,

a member acting on said guide and adapted to be driven for moving said ribbon in a transverse direction, said member being movable to different positions relative to said guide for varying said transverse movement,

a first cam means operating on each print action for driving said member,

means including an oscillatable element for effecting a stepped feeding of said ribbon longitudinally, a second cam means operating on each print action and adapted to move said oscillatable element in one direction, 5 yieldable means for urging said oscillatable element toward said second cam means, a first latch engageable with said oscillatable element for holding it either in a first position free of said second cam means or in a second position for partial drive by said second cam means, means including a control cam which is advanced in steps on each print action, 10 a first lever adapted to be actuated by said control cam for moving said member to different positions, a second lever adapted to be actuated for releasing said latch from said oscillatable element, means moving with said control cam and operating after a predetermined number of print actions for actuating momentarily said second lever to release 20 said oscillatable element for movement from the first position held to its second held position, and manually operated means for moving said first lever to a position free of said control cam and moving said second lever to a position completely 25 releasing said latch from said oscillatable element.

8. The mechanism of claim 7 including:

a manually actuated lever which is operable to move said member to any one of different positions when said first lever is moved to a position free of said control cam and said second lever is moved to a position holding said latch released, 30 a second latch engageable with said oscillatable element for holding it free of said second cam means, and a projecting portion on said manually actuated 35 lever acting on said second latch for holding it normally out of engagement with said oscillatable element, said projecting portion moving to a position for releasing said second latch when said manually actuated 40 lever is moved to a position locating said member so that no transverse motion of said ribbon takes place.

9. A mechanism for feeding an inked ribbon relative to a point of contact between a print element and a platen comprising, in combination:

guiding means for said ribbon, 45 a member acting on said guiding means for transmitting motion thereto in a direction extending transversely of said ribbon, said member being movable to different positions relative to said guiding means for varying the amount of motion transmitted, 50 means operating on each printing action by said print element for moving said member to a different one of said different positions, means operating on each printing action for driving 55 said member to effect movement of said guiding means,

and means operating after a predetermined number of print actions for advancing said ribbon a unit distance longitudinally, 60 said means for moving said member to a different one of said different positions and said means for advancing said ribbon comprising a ratchet wheel, means operating on each print action for stepping said ratchet wheel,

a cam fixed to said ratchet wheel for rotation therewith, means including a lever actuated by said cam and operatively connected to said member for moving the latter, and means including an element rotating with said ratchet wheel and operating on each rotation of the latter for advancing said ribbon. 70

10. A mechanism for feeding an inked ribbon relative to a point of contact between a print element and a platen wherein the ribbon is of the type which is fed longitudinally once past said point of contact and discarded comprising, in combination:

guiding means for said ribbon, 5 a member acting on said guiding means for transmitting motion thereto in a direction extending transversely of said ribbon, said member being movable to different positions relative to said guiding means for varying the amount of motion transmitted,

means operating on each printing operation of said print element for moving said member to a different one of said different positions, means operating on each printing operation of said print element for driving said member to effect movement of said guiding means, means for advancing said ribbon longitudinally a predetermined distance in response to and during at least a portion of the print operations,

and means interconnecting said means for moving said member to a different one of said different positions and said means for advancing said ribbon longitudinally to cause at least portions of the areas of said ribbon brought to printing position during successive print operations to overlie a line extending transversely and perpendicularly to the longitudinal direction of advance of said ribbon across the width of said ribbon.

11. A mechanism for feeding an inked ribbon relative to a point of contact between a print element and a platen wherein the ribbon is of the type which is fed longitudinally once past said point of contact and discarded comprising, in combination:

means including a cyclically operable print shaft for effecting relative movement between said print element and said platen to cause printing of characters; 50 guiding means for said ribbon; a member acting on said guiding means for transmitting motion thereto in a direction extending transversely of said ribbon, said member being movable to different positions relative to said guiding means to determine the amount of motion transmitted, means including a cam means driven from said print shaft for moving said member to a different one of said different positions on each print operation, means including a cam rotatable with said print shaft for driving said member while in any of its positions to effect movement of said guiding means, means driven from said print shaft on at least a portion of the print operations for advancing said ribbon longitudinally a predetermined distance, and means interconnecting said means for moving said member to a different one of said different positions and said means for advancing said ribbon longitudinally so that at least portions of the areas of said ribbon brought to printing position during successive print operations overlie a line extending transversely and perpendicularly with respect to the longitudinal direction of advance of said ribbon across the width of said ribbon.

12. A mechanism for feeding an inked ribbon relative to a point of contact between a print element and a platen wherein the ribbon is of the type which is fed longitudinally once past said point of contact and discarded comprising, in combination:

means including a cyclically operable print shaft for effecting relative movement between said print element and said platen to cause printing of characters; 55 guiding means for said ribbon; a member acting on said guiding means for transmitting motion thereto in a direction extending transversely of said ribbon, said member being movable to different positions relative to said guiding means to determine the amount of motion transmitted, means including a cam means driven from said print shaft for moving said member to a different one of said different positions on each print operation,

means including a cam rotatable with said print shaft for driving said member while in any of its positions to effect movement of said guiding means; means driven from said print shaft on at least a portion of the print operations for advancing said ribbon longitudinally a predetermined distance, 5 means interconnecting said means for moving said member to a different one of said different positions and said means for advancing said ribbon longitudinally so that at least portions of the areas of said ribbon brought to printing position during successive print operations overlie a line extending transversely and perpendicularly with respect to the longitudinal direction of advance of said ribbon across the width of said ribbon, 10 means interconnecting said means for moving said member to a different one of said different positions and said means for advancing comprising a ratchet wheel, 15 pawl means operating on said ratchet wheel for stepping the same on each print operation, said cam means being associated and rotatable with said ratchet wheel, and an element rotating with said ratchet wheel for actuating said means for advancing said ribbon longitudinally. 20

13. A mechanism for feeding an inked ribbon relative to a point of contact between a print element and a platen wherein the ribbon is of the type which is fed longitudinally once past said point of contact and discarded comprising, in combination: 25

means including a cyclically operable print shaft for effecting relative movement between said print element and said platen to cause printing of characters, guiding means for said ribbon, 30 a member acting on said guiding means for transmitting motion thereto in a direction extending transversely of said ribbon, said member being movable to different positions relative to said guiding means to determine the amount of motion transmitted, 35 40

means including a cam means driven from said print shaft for moving said member to a different one of said different positions on each print operation, means including a cam rotatable with said print shaft for driving said member while in any of its positions to effect movement of said guiding means, means driven from said print shaft on at least a portion of the print operations for advancing said ribbon longitudinally a predetermined distance, means interconnecting said means for moving said member to a different one of said different positions and said means for advancing said ribbon longitudinally so that at least portions of the areas of said ribbon brought to printing position during successive print operations overlie a line extending transversely and perpendicularly with respect to the longitudinal direction of advance of said ribbon across the width of said ribbon, 20 said means for moving said member to different one of said different positions comprising a cam follower means engaging said cam means, means to selectively move said cam follower means between effective and ineffective cam following positions with respect to said cam means, and means actuated by said means to selectively move when said cam follower means is moved to said ineffective cam following position to position said member acting on said guiding means in a predetermined position and to prevent operation of said means for advancing said ribbon. 30
